Primary Examiner — Elizabeth J Oswecki(74) *Attorney, Agent, or Firm* — Greenberg Traurig LLP; Nigamnarayan Acharya(57) **CLAIM**

The ornamental design for an Ohm tree ornament, as shown and described.

DESCRIPTION

FIG. 1 is a front perspective view of an Ohm tree ornament, showing my new design shown in a used condition attached to a spring stand shown in broken lines;

FIG. 2 is a rear perspective view of FIG. 1;

FIG. 3 is a front view of FIG. 1, shown in a used condition on a tree shown in broken lines;

FIG. 4 is a rear perspective view of FIG. 1, shown in a used condition attached to a cone stand in broken lines;

FIG. 5 is a front view of FIG. 4, shown in a used condition on a tree shown in broken lines;

FIG. 6 is a top view of FIG. 1; and,

FIG. 7 is a bottom view of FIG. 1.

The broken line showing of the mounting elements and the tree form no part of the claimed design.

1 Claim, 6 Drawing Sheets(56)
